CLAIM

The ornamental design for fitness bench, as shown and described.

DESCRIPTION

FIG. 1 is an exploded view, in a first embodiment;

FIG. 2 is a perspective view of the closed configuration thereof;

FIG. 3 is a perspective view of the closed configuration thereof;

FIG. 4 is a bottom perspective view thereof;

FIG. 5 is a bottom perspective view thereof;

FIG. 6 is a side view of the closed configuration, the other side being a mirror image thereof;

FIG. 7 is a top perspective view of the partially-expanded configuration thereof;

FIG. 8 is a bottom perspective view of the partially-expanded configuration thereof;

FIG. 9 is a side view of the partially-expanded configuration, the other side being a mirror image thereof;

FIG. 10 is a perspective view of the partially-expanded configuration thereof;

FIG. 11 is a bottom perspective view of the partially-expanded configuration thereof;

FIG. 12 is a side view of the partially-expanded configuration, the other side being a mirror image thereof;

FIG. 13 is a perspective view of the partially-expanded configuration thereof;

FIG. 14 is a bottom perspective view of the partially-expanded configuration thereof;

FIG. 15 is a side view of the partially-expanded configuration, the other side being a mirror image thereof;

(Continued)

FIG. 16 is a perspective view of the partially-expanded configuration thereof;
 FIG. 17 is a bottom perspective view of the partially-expanded configuration thereof;
 FIG. 18 is a side view of the partially-expanded configuration, the other side being a mirror image thereof;
 FIG. 19 is a perspective view of the expanded configuration thereof;
 FIG. 20 is a bottom perspective view of the expanded configuration thereof; and,
 FIG. 21 is a side view of the expanded configuration, the other side being a mirror image thereof.
 The broken lines in the drawings are included for the purpose of illustrating subject matter that forms no part of the claimed design.
